UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

WEATHERPROOF SOCKET.

1,279,940.

Specification of Letters Patent. Patented Sept. 24, 1918.

Application filed March 28, 1918. Serial No. 225,321.

To all whom it may concern:

Be it known that I, GEORGE B. THOMAS, a citizen of the United States of America, residing at Bridgeport, in the county of Fairfield and State of Connecticut, have invented certain new and useful Improvements in Weatherproof Sockets, of which the following is a specification.

My invention relates to weatherproof 10 sockets, and the object of my invention is to provide an improved, two-piece base construction which may be more readily manufactured than the one-piece base heretofore used, while, at the same time, insuring complete 15 inclosure of the wiring connections and a generally rugged and efficient device of the type mentioned.

In the accompanying drawings,

Figure 1 is a plan of a weatherproof 20 socket in which my invention is embodied in one form;

Fig. 2 is a broken side elevation thereof;

Fig. 3 is a plan of the body of the socket 25 with the cap removed.

Weatherproof socket bases, as hitherto manufactured, have commonly been made in one piece which completely houses the wire connections to prevent the entry of moisture into the wiring chambers with the attendant 30 danger of short-circuiting the fitting. In such one-piece construction, however, the molding and firing operations are difficult to perform without considerable losses from breakage and flaws, and there are frequent 35 delays incident to the more or less difficult steps of manufacture. According to the present invention, the socket comprises a two-piece base, both parts of which are readily manufactured and easily and expeditiously 40 united after the wiring connections have been established, the parts being then permanently secured together by means of insulating cement.

As illustrated in the accompanying drawings, my improved socket base comprises a cap 10 and body 11, both of insulating material such as porcelain. The cap 10 is provided with an upstanding rib 12 perforated at 13 to receive a suspension hook or the like, and at 14 and 15 to permit the passage of the wire cables 16 and 17 therethrough. On opposite sides of the rib 12, the cap is pierced at 18 and 19 to afford pouring apertures, and adjacent these holes are formed ledges 20 and 21 pierced to permit the passage there-

through of the shanks of the securing screws 22 and 23, by means of which the cap and body are united. The lower face of the cap is recessed at 24 to form a seat for one end of the socket body 11, beyond which the 60 skirt 25 of the cap extends to form a rain shed.

The body 11 of the socket comprises a cylindrical casing closed toward the cap end by a diaphragm 26. The shallow chamber 65 formed between this diaphragm and the cap 10 is subdivided by a transverse partition 27 into two compartments. Wire terminal plates 28 and 29 are secured in these two compartments and are arranged at the bottoms of shallow channels which communicate with passages 30 and 31 cut in the marginal end flange 32 of the socket body 11, and through which the bared ends of the cables 16 and 17 are led in to the terminal 75 plates 28 and 29 and soldered thereto as indicated at 33 and 34, Fig. 3.

Within the well lying on the opposite side of the diaphragm 26 are seated the socket shell contact 35 and the center contact 36. 80 The shell 35 is electrically connected to the terminal 28 by the screw 37 which passes through the bottom flange of the shell, pierces the diaphragm 26, and takes into a tapped hole in the terminal plate 28. The 85 center contact is secured by the screw 38 which passes through one end of the strap, pierces the diaphragm 26, and takes into a tapped hole in the other terminal strap 29.

Overlying the base flange of the screw 90 shell 35 is an arcuate plate 39 tapped to receive the screws 22 and 23. The latter are so located that they overlie the barrier 27, and the piercings, which accommodate the screws, pass through the enlarged ends 95 of the barrier as clearly shown in Fig. 3. The screws are thus completely inclosed and insulated from the wire terminals located in the compartments lying on each side of the diaphragm. In order to facilitate the proper positioning of the cap on the body, a stud 41 is formed on the lower face of the cap which takes into a notch 40 in the end flange 32 of the body.

After the bared ends of the cables 16 and 17 have been soldered to the terminal straps 28 and 29, and the cap 10 secured in position by means of the screws 22 and 23, insulating composition 42 is poured into the respective wiring compartments through 105 110

the holes 18 and 19, and completely fills these compartments, the pour holes, and overlies the heads of the securing screws 22 and 23, and thus completely seals the cap 5 10 and body 11 in their assembled position. The outer ends of the cables 16 and 17 are then passed through the holes 14 and 15 in the rib 12 to form sharp angles around the margins of the cap flange 25 and at the 10 rib 12, thus affording strain-relieving means which minimizes the likelihood of injury to the soldered connections at the respective terminal plates 28 and 29.

The manufacture of the two parts 10 and 15 11, which together constitute the insulating base of the receptacle is readily accomplished at comparatively small expense; the wiring of the fitting is more easily performed than has heretofore been possible; 20 the assembly of the cap and body by means of the screws 22 and 23 is a simple matter; and the sealing of the terminal chambers and the openings thereto by the pouring of insulating cement through the holes 18 and 25 19, is expeditiously accomplished. The completed fitting is as perfectly weatherproofed as a one-piece receptacle and constitutes a workmanlike and efficient article. I do not limit my invention to the precise 30 form illustrated nor to the details of construction illustrated, which may be variously departed from within the scope of what I claim as my invention.

I claim:

35 1. A weatherproof socket comprising an insulating base having independent cap and body parts, and means for uniting said parts together, said body part being recessed at the cap end to afford a wiring recess, and

channels leading thereto from opposite sides 40 through which the wire ends may enter, wire terminals in said recess, said cap being pierced to admit insulating cement to the wiring recess.

2. A weatherproof socket comprising an 45 insulating base having independent cap and body parts, and means for uniting said parts together, said body part being recessed at the cap end to afford a wiring recess and having a cross barrier subdividing said recess into two wiring compartments, wire entry channels leading to said compartments, wire terminals in said compartments, said cap being pierced by a pair of pour apertures leading respectively to 55 the two wiring compartments and through which insulating cement may enter the said compartments.

3. In a construction such as recited in 60 claim 2, means for uniting the cap and body together comprising screws passing down through the cap and said barrier on the body, substantially as described.

4. In a weatherproof socket, independent 65 cap and body portions shaped to confine between their adjacent faces a wiring chamber, said cap being pierced to admit insulating cement to the wiring chamber and being recessed in communicating with said piercing to afford a ledge for the head of a securing screw, said recess and piercing being completely filled and said ledge and securing screw head completely covered with insulating cement in the completed 70 socket.

75 In testimony whereof I have signed my name to this specification.

GEORGE B. THOMAS.
